UNITED STATES PATENT OFFICE.

OTTO G. PAINTER, OF CLEVELAND, OHIO, ASSIGNOR TO THE BETTCHER MANUFACTURING COMPANY, OF CLEVELAND, OHIO, A CORPORATION OF OHIO.

BEAM-CLAMP.

1,160,194.

Specification of Letters Patent. Patented Nov. 16, 1915.

Application filed December 21, 1914. Serial No. 878,416.

To all whom it may concern:

Be it known that I, OTTO G. PAINTER, a citizen of the United States, resident of Cleveland, county of Cuyahoga, and State 5 of Ohio, have invented a new and useful Improvement in Beam-Clamps, of which the following is a specification, the principle of the invention being herein explained and the best mode in which I have contemplated 10 applying that principle, so as to distinguish it from other inventions.

My invention relates to beam-clamps such as are used for engaging the bases of ordinary I-beams, through the medium of 15 which a hanger may be secured to such beam for the purpose of supporting any desired object, as for instance, a line of pipe.

The object of the invention is to provide a beam-clamp which will be economical of 20 manufacture, simple of adjustment and efficient in its operation.

The said invention consists of means hereinafter fully described and particularly set forth in the claims.

25 The annexed drawings and the following description set forth in detail certain means embodying my invention, the disclosed means, however, constituting but one of various mechanical forms in which the principle of the invention may be applied.

In said annexed drawings: Figure 1 represents a front elevation of a beam-clamp embodying my invention, showing a fragmentary portion of the depending hanger, 35 and a cross-section of a fragmentary portion of an I-beam, the members of the clamp being shown in their expanded position prior to adjustment to the beam. Fig. 2 represents the parts shown in Fig. 1 showing 40 same adjusted to and engaging the beam base. Fig. 3 represents a side elevation of the beam clamp, the depending hanger and a cross-section of pipe, together with a side elevation of a fragmentary portion of a beam. Fig. 4 represents a front elevation of the parts shown in Fig. 3 showing the members of the clamp in a modified position. Fig. 5 is a view similar to that of Fig. 1 showing a modified form of clamp. Fig. 6 45 represents a side elevation of the modified form of clamp and depending hanger of a fragmentary portion of the pipe shown, as well as a cross-section of the fragmentary portion of the beam. Fig. 7 represents a

vertical section taken upon the plane indicated by line VII—VII in Fig. 6 and Fig. 8 represents a similar section taken upon the plane indicated by line VIII—VIII in said figure.

The illustrated embodiment of my invention includes two members 1, 1, which are exactly similar in form and construction. One end of each of these members is formed with a hook 2 in the usual manner whereby such end may be caused to engage one side 55 of the base 3 of an I-beam 4. The main or body portion 5 of each such member extends substantially parallel with the base of the I-beam when its hook is engaging same as above described, and as illustrated in Fig. 2. 60 This body portion is formed with a longitudinally extending slot 6 which extends through each portion and which is bounded at the top and bottom by two serrated surfaces 7, 7, respectively, these surfaces forming 65 alternating teeth and spaces. These surfaces are so formed that the teeth formed by one surface will be disposed opposite to the spaces of the other surfaces, as clearly shown in Fig. 1. These two members 70 when in their operative position are placed so that the body portions are in juxtaposition to the slots 6 in apposition to each other, the hook portions being at opposite 75 ends of the combined structure thus formed. 80 Extending through the slots is a shank 8 of a bolt 9 and this bolt therefore through the medium of the nut 10 may be used to clamp the two members securely together 85 and prevent their longitudinal movement 90 with reference to each other. The hanger 11 is provided in the usual manner with a plurality of holes 12, through the upper one 95 of which passes the shank of the bolt 9.

In applying the above-described structure, the parts are first assembled, the nut 10, however, being unscrewed so as to permit the parts to be loosely connected. In this condition, the clamp and attached hanger may be carried up to the I-beam 100 and the two members 1, 1, slid upon each other until they properly engage the base of such beam, as shown in Fig. 2. The nut 10 then being screwed up tightly, the whole structure is secured in place. The position 105 of the slots is such that when these two members engage the I-beam base as shown, the upper teeth of the one member will be

opposite the lower teeth of the other member, as shown in Fig. 4. This forms a rectangular space 13 which is almost completely inclosed and through which the 5 shank 8 of the bolt extends. The width of the slot and the diameter of the shank are such that the uninclosed portion of these spaces are narrower than the diameter of the bolt shank, so that the latter, therefore, can 10 move laterally from such spaces, as will be apparent from an inspection of Fig. 2. This construction, therefore, is such that the bolt, after the parts have been tightened up, and hence the hanger, cannot be displaced in a 15 direction longitudinal with respect to the clamp.

It sometimes occurs that the continued application of the weight carried by the hanger will cause the beam-clamp to sag at the 20 center, as shown in Fig. 4. When this action occurs, it will be noted that the space 13 still further contracts and still more securely locks the bolt against such described displacement. In the modified form shown 25 in Fig. 5, I have provided the outer ends of the body portions of each of said clamps with a protuberance 14, such protuberances being preferably formed by partially punching the metal out of the said body portion, 30 by means of a suitable punch and die. These protuberances are of a diameter such that they may enter the slots and are placed on similar sides of these body portions so that when the latter are placed in their assembled 35 position, the said protuberances will project from the interior or opposed surfaces of the body portions in said slots, as shown. These protuberances therefore prevent the sagging of the two members as 40 illustrated in Fig. 4 and maintain a substantial parallelism of the said two members to each other.

Inasmuch as I-beams are of a standard size and the bases thereof are therefore of 45 a standard width, which sizes vary from each other by one half inch, the longitudinal distance from tooth to tooth of those teeth formed by the said surface is made one half inch.

50 In the above described manner therefore I obtain a simple and efficient pipe hanger constituent parts of which may be completely assembled, though loosely, before being applied to the beam. This enables the 55 operator to carry the complete device up to the beam, adjust same and secure the parts in place, without dropping or losing any of them during the operation, the result of all of which is a considerable saving of time in 60 the application of the clamp to the beam,

as will be readily understood by those skilled in the art.

Having fully described my invention, what I claim and desire to secure by Letters Patent is:—

65 1. In a beam-clamp, the combination with two members adapted respectively to engage opposite sides of a beam, each formed with a slot bounded by a serrated surface; of means adapted to pass through such slots when placed in apposition and to secure said members to each other.

2. In a beam-clamp, the combination with two members adapted respectively to engage opposite sides of a beam, each formed with a slot bounded by two oppositely disposed serrated surfaces; of means adapted to pass through said slots when placed in apposition and to secure said members to each other.

80 3. In a beam-clamp, the combination with two members adapted respectively to engage opposite sides of a beam, each formed with a slot bounded by two oppositely disposed serrated surfaces, the teeth formed by one 85 of said surfaces being disposed opposite the spaces formed by the teeth on the opposite surface; of means adapted to pass through said slots when placed in apposition and to secure said members to each other.

90 4. In a beam-clamp, the combination with two members, one end of each of which is adapted to engage one side of a beam, each such member being formed with an elongated slot and a protuberance at the other end thereof; said protuberance being adapted to simultaneously engage said slots when the latter are placed in apposition; of means adapted, when said members are so placed, to pass through said slots and secure said members to each other.

95 5. In a beam-clamp, the combination with two members, one end of each of which is formed with a hook so as to permit it to engage one side of the base of an I-beam, and formed with a body-portion which when engaging said beam extends substantially parallel with the base thereof; said body portion being formed with a longitudinally extending slot and a transversely extending 100 protuberance adjacent to the outer end of and adapted to engage such slot; the protuberances being located upon similar sides of said members respectively.

105 Signed by me, this 17th day of December, 1914.

OTTO G. PAINTER.
